UNITED STATES PATENT OFFICE.

WILLIAM F. HAUPT, OF ORANGE, NEW JERSEY, ASSIGNOR TO THE BATES MANUFACTURING COMPANY, OF WEST ORANGE, NEW JERSEY, A CORPORATION OF NEW JERSEY.

NUMBERING MACHINE.

Application filed March 10, 1927. Serial No. 174,298.

My invention relates to numbering machines and particularly to that class of numbering machines which are automatic in their action and which are usually so made that they permit the user to print numbers consecutively, or to print each number several times before the machine automatically changes the units wheel to effect the printing of the next higher number upon the next operation thereof, or to repeat the printing of the same number over and over again. The machine shown and described herein as a preferred embodiment of my invention, is constructed and arranged so that it may be set to repeat, to print consecutively, to duplicate, to triplicate, to quadruplicate, to quintuplicate, to sextuplicate, to septuplicate, and to octuplicate—the machine thus being capable of being set into nine different adjusted positions or, in other words, having nine different "index settings" and being what is known as a "multiple-movement" machine. My invention, however, is subject to great variation in the direction just noted, and may be embodied in a machine having a range of settings either greater or less than that indicated. As a matter of fact, the number of settings of this character possible in a machine constructed in accordance with my invention is practically unlimited except by consideration of such factors as size, convenience and manufacturing economy.

In some aspects, the present invention is an improvement on that disclosed in my U. S. Patent No. 1,474,715, dated November 20, 1923. However, while it is especially designed for a numbering machine of the type disclosed in said patent, my invention is equally well adapted for application to practically all other types of automatic numbering machines, including various forms of both "inside" and "outside" operated machines.

Generally stated, my invention resides in an improved and simplified construction and arrangement whereby the range of usefulness of numbering machines in which the same is embodied may be enlarged or varied as described, without increasing the complexity of the mechanisms of such machines and without involving material changes or loss of time in the process of manufacturing

the same, and whereby wear and interference of the parts are reduced to a minimum.

55

One of the objects of my invention is to provide in numbering machines such as described, a simple and improved form of control mechanism for the usual working or stepped pawls, or equivalent devices, which mechanism, preferably without requiring any undue changes in its construction or any variation in the number of its parts, renders it possible to readily adapt such machines for any desired number of settings or combinations of settings.

65

Another object of my invention is to provide a numbering machine with a control mechanism of this character and preferably comprising but a single main controlling member, preferably in the form of a control ratchet, which mechanism directly controls the working pawl, or equivalent device, and which is itself preferably directly operable by the latter.

75

A further object of my invention resides in the provision of a numbering machine which is very compact and the settings of which may be changed as desired, that is, which may be indexed, without involving the lateral or sidewise shifting either of the working pawl, or equivalent device, or of the control mechanism for the latter.

80

A still further object of my invention is to provide simple, effective and preferably semi-automatic means for re-setting the control mechanism of a numbering machine, that is, for indexing such machine, whereby the turning of a single indexing number, such as a dial, will effect the proper adjustment of the control mechanism for its new setting or index position so as to ensure the control mechanism becoming operative at the beginning of such setting or index position.

95

Other objects and features of my invention will be hereinafter more specifically described and claimed.

While my invention is capable of expression in various mechanical forms, for purposes of illustration, the preferred form of my invention as applied to a numbering machine of the type disclosed in my said Patent No. 1,474,715, is shown in the drawings accompanying and forming part of this specification, in which drawings,—

105

Figure 1 is a view in front elevation, partly broken away, of a numbering machine with my invention applied thereto;

Fig. 2 is a view in side elevation, partly broken away and partly in section, looking from the right in Fig. 1;

Fig. 3 is an enlarged fragmental view similar to Fig. 2, the machine being on consecutive setting and the parts being shown in printing position;

Fig. 4 is a view similar to Fig. 3 with the plunger box or numbering wheel head and the parts carried thereby in their raised or normal position;

Fig. 5 is an enlarged detailed view in side or end elevation, partly in section, showing the working pawl, the control mechanism therefor when in the octuplicate setting, and the retaining pawl and lift lever associated with the control mechanism, the parts being shown in the position they occupy at the beginning of the actuating stroke of the working pawl;

Fig. 6 is a view similar to Fig. 5 with the parts shown in the position they occupy at the end of the actuating stroke of the working pawl;

Fig. 7 is a view similar to Fig. 5 with the parts shown in the position they occupy at the finish of the return or reverse motion of the control ratchet;

Fig. 8 is a view in elevation looking from the right in Fig. 7 and showing some of the numbering or type wheels in broken lines;

Fig. 9 is a view similar to Fig. 5 with the control mechanism in the repeat setting, the parts being shown in the position they occupy at the end of the working stroke of the working pawl;

Fig. 10 is an enlarged view in perspective of one of the numbering or type wheels and the working or stepped pawl associated therewith;

Fig. 11 is an enlarged detailed view in perspective showing parts of the indexing mechanism and the working pawl control mechanism which is adapted to be set or adjusted thereby; and

Fig. 12 is an enlarged sectional view, partly in elevation, of the indexing mechanism, the section being taken on line 12-12 of Fig. 1 looking in the direction of the arrows.

Referring to the drawings, reference character 1 represents the main frame of the machine, said frame being in the form of an inverted U and having the numbering wheel head and the principal operating mechanism of the machine mounted between its legs. A plate 2 is suitably secured to the lower ends of the legs of frame 1 and has an opening 3 through which the type of the numbering or type wheels project in printing or stamping the numbers, as indicated in Fig. 3, and at the edges of which the usual printing

guides, not shown, are cut. At its top the frame 1 is provided with a collar 4 through which reciprocates the usual tubular spindle 5 of the numbering wheel head, such spindle having the handle 6 detachably connected to its upper end. Within the spindle 5 and handle 6 is disposed a helical spring 7 which acts normally to hold the numbering wheel head in its raised position as shown in Figs. 1, 2 and 4, as is usual in this type of numbering machines. Below the spring 7 and extending through the collar 4 and spindle 5 is a pin 8 free to be moved transversely, but having no vertical movement. The spindle 5 is slotted at 9, 9 to permit of its movement past the pin 8. One of the slots 9 is enlarged as indicated at 10, at its upper end portion to about the size of the head of pin 8, but this enlarged portion is not cut all the way through the material of the spindle, as shown in Fig. 1, and accordingly when the enlargement 10 in the downward movement of the spindle 5 is aligned with pin 8, the latter may be moved in the direction of its length so as to engage the head thereof with such enlargement and thereby effect the locking of the spindle together with the numbering wheel head and the parts carried thereby in depressed position. The numbering wheel head, indicated at 11, is in the form of a yoke or inverted U, and a barrel 12 is mounted in a horizontal position between the legs or depending side members of said yoke and fixedly secured in such position as by means of screws, not shown, extending through said side members and threaded into the adjacent ends of the barrel. A shaft 13 is mounted for oscillatory movement in an axial opening extending through the barrel 12, said shaft fitting quite closely with said opening and extending a considerable distance from each end of the barrel and beyond the sides of the head or yoke 11 through openings 12' provided in said sides, into vertical guide-ways 14 provided in the legs of the main frame 1, the ends of said shaft being closely adjacent the bottom of the respective guide-ways. Anti-friction rollers 15 mounted on the ends of shaft 13 and disposed in the guideways 14 coat with the latter to guide the head 11 in its reciprocatory movements in the main frame 1. The type or numbering wheels 16, of which there are seven in the machine illustrated, are annular in form and are arranged side by side within the yoke or head 11 and rotatably mounted on the barrel 12 fixed to the head, these numbering wheels being respectively the usual units, tens, hundreds, thousands, tens of thousands, hundreds of thousands and millions wheels. Other suitable series of wheels may be employed and the number of such wheels used may, of course, also be varied as desired. The wheels 16 are maintained in slightly spaced relation on the bar-

rel 12 as by means of thin ring washers, only one of which is indicated at 17 in Fig. 8, which are respectively disposed between adjacent wheels and which are preferably held 5 against rotary movement in any suitable manner, as by having inward projections, not shown, conforming to and disposed in a longitudinal recess 18 in the barrel. A spacing ring, not shown, is also preferably loosely 10 mounted on the barrel 12 between the numbering wheel 16 of the highest order and the adjacent leg or side member of the yoke or head 11. Reference characters 19 and 20 represent annular members comprising parts 15 of my improved control mechanism for controlling the operations of the working or stepped pawl, or equivalent device, for various settings of the machine, said members being respectively referred to herein as the 20 "control ratchet" and the "control ratchet governor." The members 20 and 19 are rotatably mounted in spaced relation on the barrel 12, in the order named, between the units wheel 16 and the adjacent leg or side 25 member of the head or yoke 11. These members 19 and 20 are resiliently connected as by means of a spiral spring 22 which, as shown, is secured at the inner end to an inner annular flange or hub 20' of the control ratchet 30 governor or member 20 and at its outer end to a projection 23 which is provided on the control ratchet 19 at the outer edge or perimeter of the latter and which extends laterally therefrom so as to overly the member 20 35 and be in the path of a projection or tooth 24 formed on the outer edge of the said member 20. The spring 22 constantly tends to maintain the control ratchet 19 in such a position relative to the control ratchet governor 20 that the lateral projection 23 of the former will be in engagement with the tooth or stop 24 on the latter, and the arrangement is such that rotary movement of the control ratchet with respect to the ratchet governor 40 to the left, referring to Figs. 5, 6, 7 and 9, that is, in such direction that the projection 23 is moved away from the projection or stop 24 on the control ratchet governor, will wind up or increase the tension of this spring. 45 Each of the numbering wheels 16, as is usual, is provided with nine shallow notches 26 and deep notch 27 in the inner annular edge thereof, these notches being equispaced and having the usual disposition, i. e., there 50 is one shallow notch 26 for each of nine numbers on the wheel and the deep notch is employed for the tenth number and for the purpose of "carrying" to the wheel which is of the next order. Where my invention, as 55 shown herein, is adapted to a nine-movement machine, the control ratchet 19 is provided on its inner periphery with a series of seven equispaced notches, six of which are shallow notches 28 and one end notch 29 of 60 the series being deep and long. The inner periphery of this control ratchet also has a long smooth or unnotched section 30 between the deep notch 29 and the end shallow notch 28 therein. No notches, however, are provided in the inner periphery of the control 65 ratchet governor 20, such periphery being smooth for its entire length.

Crank arms 32 are respectively secured intermediate their ends to the projecting end portions of the shaft 13 outside the 70 legs or side members of the yoke or head 11 and between such side members and the legs of the main frame 1, such arms being provided at one end with inwardly-directed pins 33 and at their other end with slots 34. 75 The working pawl comprises a pawl bar 36, having a series of integral stepped pawls 37 corresponding in number with and adapted to respectively coact with the numbering 80 wheels 16 and also having an integral single 85 pawl or tooth 38 adjacent one end, the pawl 38 being adapted to coact with the control ratchet 19 and being slightly longer in a radial direction than the adjacent longest pawl 90 or tooth of the series of stepped pawls 37 and spaced therefrom by a deep wide notch 39. The pawl bar is pivotally supported from and between the crank arms 32, said 95 bar being provided at its ends with aligned openings 40 with which the pins 33 on the 100 crank arms respectively engage, and being received within the usual longitudinal recess 41 formed in the barrel 12. The recess 41 is of sufficient size to accommodate the 105 pawl bar 36 in the movements thereof when in all the various positions it assumes in the operation of the machine. The spacing washers 17 are each provided at a point 110 therein opposite the recess 41 in the barrel 12, with a large recess, not shown, preferably substantially of the form of the notch 29 in the control ratchet 19, to accommodate the 115 pawl bar 36 in the movement thereof when in its outward actuating positions. The openings 12' in the side members or legs of the 120 head 11 are also of such size and shape as to freely accommodate the pawl bar 36 in the oscillatory movements thereof in the various 125 positions it occupies for all the different settings of the machine. A torsion spring 43 coiled about the pivot pin 33 of one of the crank arms 32 and bearing at one end against said crank arm and at the other end against the pawl bar 36, constantly tends to force the pawl bar outwardly about the pivot pins 33 and into coacting engagement with the notched inner peripheries of the annular numbering wheels 16 and control ratchet 19.

When the yoke or head 11 is reciprocated in the main frame 1, the shaft 13 and the pawl bar 36 carried thereby are oscillated to advance the numbering wheels by the usual step-by-step movements, it being understood, 130 of course, that when the machine is set for

"duplicate" or "triplicate" or "quadruplicate", or "quintuplicate", etc., the pawl bar will be held from coacting with or advancing the numbering wheels except during 5 every second, or every third, or every fourth, or every fifth, etc., reciprocation of the head 11, while when the machine is set for "repeat", the pawl bar will be continuously held from coacting with or advancing the 10 numbering wheels. Such oscillatory movement is imparted to the shaft 13 and the pawl bar 36 upon the up and down reciprocatory movements of the head 11, by the U-shaped ink pad frame 45 carrying the pad 15 46 for inking the type or numbers of the wheels 16 and pivotally supported from the head 11 by pins 47 which extend through the angular legs 48 of said frame and into the adjacent side members or legs of the head. 20 Adjacent the pivot pins 47 and at the ends thereof remote from the pad 46, the legs 48 of the frame 45 are provided with pins 49 which respectively engage the slots 34 of the crank arms 32 which are fixed to the 25 shaft 13, and at or adjacent their angle or bend, these legs are provided with similar slots 50 which are respectively slidably engaged by reduced smooth end portions of pins or screws 51 secured to and extending 30 inwardly from rearwardly extending portions 52 provided on the legs of the main frame 1. The arrangement is such that as the numbering head 11 is reciprocated in frame 1, the pins 51 coact with slots 50 to 35 effect movement of the ink pad frame 45 about the axes of pivot pins 47, this frame in the down movement of the head 11 being moved outwardly about the pins 47 to that position in which the ink pad 46 is most 40 remote from the numbering wheels, as shown in Fig. 3, and being moved inwardly about the pins 47 to the position shown in Figs. 2 and 4 with the pad 46 pressed firmly 45 against the type of the wheels 16 which are to perform the next printing, on the up movement of head 11. In such pivotal movement of the ink pad frame the pins 49 fixed to the legs 48 thereof coact with the slots 34 of the crank arms 32 to oscillate the 50 latter and thereby the shaft 13 and pawl bar 36, the return movement or stroke of the pawl bar being effected upon the outward movement of the ink pad frame 45 and the down-stroke of the head 11 and the forward 55 or working stroke of the pawl bar being effected upon the inward movement of frame 45 and the up-stroke of head 11. With the arrangement described, however, the pawl bar 36 is held by reason of the engagement 60 of its long tooth or pawl 38 with the inner periphery of the control ratchet 19, from coaction with the numbering or type wheels 16 at all times except when the control ratchet is in a position in which the large 65 clearance notch or recess 29 thereof is di-

rectly opposite the pawl bar so as to accommodate the latter within the limits of the oscillatory movement imparted to it through the crank arms 32. When the control ratchet is thus positioned, the notch 29 70 therein permits the stepped or working pawl to engage the type or numbering wheels, and this pawl will then, upon each of its working strokes, actuate or advance said wheels. Such working strokes of the stepped or 75 working pawl will be referred to herein as actuating strokes.

The "settings" of the machine are determined by the settings or initial positions given to the control ratchet 19 by indexing 80 mechanism, which will be hereinafter more fully described, through the control ratchet governor 20. By such indexing mechanism the governor 20 is adapted to be moved to and firmly but yieldingly or releasably 85 locked in any of nine angular positions corresponding to the nine settings of the machine, on the barrel 12. When moved to any of these positions the governor 20 will carry the control ratchet 19 with it by reason of the resilient connection between these members consisting of the spiral spring 22, this spring as indicated above always tending to maintain the control ratchet in a position with its lateral projection 23 engaging the peripheral projection or tooth 24 of the ratchet governor. When the control ratchet is thus set to an initial position in which only the smooth or unnotched portion 30 of its inner periphery will be engaged by the tooth 90 or pawl 38 of the pawl bar 36, in the oscillatory working and return strokes of the latter effected, as described, upon reciprocatory movement of the plunger or numbering head 11, it will be obvious that neither the control 95 ratchet nor the numbering wheels will be advanced or actuated in the working strokes of the pawl bar and that consequently, in the operation of the machine under these 100 conditions, none of the working strokes of the pawl bar will be actuating strokes and the machine will "repeat" or print the same 105 number or characters over and over. This "repeat" setting of the control ratchet 19 is illustrated in Fig. 9.

When the ratchet governor 20 is moved by the indexing mechanism so as to carry the control ratchet 19 to an initial position in which the large recess or clearance notch 29 thereof will accommodate the pawl device 120 36 in the entire range of its oscillatory movement consisting of the working and return strokes thereof, the control ratchet will obviously not act to prevent the pawl device 125 from coacting with the type wheels and accordingly upon each working stroke the pawl device will actuate or advance one or more of the type or numbering wheels, in other words, when the control ratchet is set, as described, each working stroke of the 130

pawl device will be an actuating stroke. The machine will then operate to print consecutively, which is the normal operation of a machine of the type herein described.

5 This "consecutive" setting of the machine and the operation of the machine in such setting are shown in Figs. 3 and 4.

To effect any setting of the machine other than the "repeat" and "consecutive" settings, already described, the indexing mechanism is operated to turn the ratchet governor 20 so that it will set the control ratchet 19 in an initial position in which a certain number of the notches 28 and 29 of the 15 notched section of the inner periphery of the control ratchet, dependent upon whether such setting of the machine is the duplicate, triplicate, quadruplicate, quintuplicate, sextuplicate, septuplicate, or octuplicate setting, 20 are adapted to successively coact with the pawl bar or device 36 in the operation of the machine, to effect a step-by-step advance movement of the control ratchet upon the successive working strokes of the pawl device. Any such advance movement imparted 25 to the control ratchet is not partaken of by the ratchet governor 20, as the latter is yieldingly locked by the indexing mechanism in the position to which it and the control 30 ratchet were initially set by such mechanism, and moreover the pawl bar 36 never tends to advance the ratchet governor as the latter is not only free from notches on its inner periphery but is also never engaged by the 35 pawl bar due to the fact that it registers with the deep recess 39 provided in said bar between the pawl or tooth 38 and the next adjacent pawl 37. This advance movement 40 of the control ratchet, however, is opposed by and acts to wind up the spiral spring 22, and in order to retain the ratchet in its advanced position after each step-wise movement imparted to it upon a working stroke 45 of the pawl bar 36 and during the return stroke of the latter, said ratchet is provided on a portion of its outer periphery with a 50 series of ratchet teeth 56 and 57, corresponding in number to the notches 28 and 29 in its inner periphery, and a retaining member 55 or pawl 58 is pivotally mounted in such a position on a stud 59 carried by the adjacent leg or side member of the yoke or head 11, that its tooth 60 is adapted to coact with 60 said ratchet teeth. A leaf spring 61 secured 55 to the yoke or head 11 bears against the retaining pawl 58 and tends to constantly force the same towards the control ratchet 19, the arrangement being such that the tooth 60 of the retaining pawl normally 65 glides over the ratchet teeth 56 and 57 during the step-wise advance movement of the control ratchet effected by the working strokes of the pawl bar 36, but coacts with the ratchet teeth 56 to prevent return or 70 reverse movement of the control ratchet un-

der the action of the spring 22, during the return strokes of said pawl bar. After a certain number of complete oscillations of the pawl bar 36, depending on the initial positioning or setting of the control ratchet 70 19 by the indexing mechanism through the control ratchet governor 20, the ratchet 19 is brought to the position shown in Fig. 5 in which the large recess or notch 29 therein permits the pawl bar to engage one or more 75 of the type or numbering wheels 16. During each of such number of complete oscillations of the bar 36, comprising both a working stroke and a return stroke of the latter, the inner peripheral portion of the ratchet having the notches 28, prevents the pawl bar from engaging any of the type wheels 16, and accordingly the same number is printed in each actuation of the machine resulting 80 in such an oscillation of the pawl bar. The 85 next working stroke of the pawl bar 36, however, is an actuating stroke and in such stroke said bar actuates or advances one or more of the type wheels 16. It will thus be seen that for any setting of the machine 90 other than the "repeat" and "consecutive" settings, a certain number of working strokes must be imparted to the pawl bar 36 before an actuating stroke thereof is effected. Upon the completion of such an actuating 95 stroke of the pawl bar 36, the control ratchet 19 is returned or reversed to its initial position or setting by the spring 22, this spring being then rendered free to act by simultaneously releasing the working pawl 36 and 100 the retaining pawl 58 or, in other words, by moving said pawls 36 and 58 to positions in which they are no longer respectively in coactive relation with the notched inner periphery and the toothed outer periphery of 105 the control ratchet. The working pawl 36 must now go through another cycle of strokes such as that just described, before the type wheels 16 are again advanced; and it will be apparent that repetitions of this 110 cycle are obtainable as often as the control ratchet 19 is returned or reversed to its initial position or setting after successive actuating strokes of the working pawl. The simultaneous release of the control ratchet 115 19 by both the working pawl or pawl bar 36 and the retaining member or pawl 58, at the completion of each actuating stroke, is automatically effected by the movement of a lever 63, which I shall refer to as the lift 120 lever, to the position shown in Figs. 6 and 7, wherein a smooth curved edge portion 64 thereof engages a portion of the tooth or pawl 38 of the pawl bar extending outwardly 125 beyond the control ratchet, to hold such tooth out of engagement with the inner periphery of the control ratchet, and wherein a pin 65 carried thereby coacts with a cam surface 66 provided on the upper end portion of the retaining member or pawl above 130

the tooth 60, to hold said retaining member against the action of spring 61 in a position in which the said tooth 60 is out of the path of the ratchet teeth 56 and 57. The lift lever 63 is mounted on a pivot screw or stud 68 secured to and extending inwardly from the adjacent leg or side member of the yoke or head 11, and a spring 69 bearing at one end against the yoke 11 and secured at its other end to the lift lever constantly tends to move the latter inwardly about the pivot 68 to the operative position thereof, shown in Figs. 6 and 7. The lift lever, however, is normally held in raised inoperative position against the action of spring 69, as shown in Figs. 3, 4, 5 and 9, by the engagement of the upper end 70 of the retaining member or pawl 58 with the pin 65 of said lever. The said end 70 of the member 58 is concentric with the stud 59 and of such a length that the pin 65 of the lift lever remains in engagement therewith to retain the said lever in its raised inoperative position, during the oscillatory movement imparted to the said member by reason of the engagement of the tooth or pawl 60 by the ratchet teeth 56 in the step-by-step advance movement of the control ratchet 19, but is moved wholly from beneath said pin to thereby release the lift lever, when the tooth 60 is engaged by the high end ratchet tooth 57. The arrangement is such that the ratchet tooth 57 is engaged with the tooth 60 of the retaining pawl in the actuating stroke of the pawl bar 36 and the release of the lift lever 63 effected substantially at the completion of such actuating stroke. The lift lever thereupon immediately drops or moves, under the action of spring 69, to its operative position in which the curved surface 64 and pin 65 thereof respectively coact with the pawl bar 36 and the cam surface 66 of the retaining pawl 58 to move said bar and retaining pawl to and hold the same in positions in which they are disengaged from and entirely free of the control ratchet 19; the parts then being in the positions shown in Fig. 6. A pin or stud 72 on the lift lever extends through a slot 73 provided in the adjacent leg of the head 11 and coacts with the lower end of said slot to limit the inward or downward movement of the lift lever. The control ratchet 19 being thus released the spring 22 acts to at once return the same to its initial position with the projection 23 thereof in engagement with the tooth or stop 24 on the control ratchet governor 20, and upon the completion of the next return stroke of the working pawl 36 the parts occupy the positions shown in Fig. 7. Upon the following working stroke of the working pawl 36 it is necessary to effect the return of the lift lever 63 to its normal raised position and thereby the re-

engagement of both the working pawl and 65 the retaining member or pawl 58 with the control ratchet 19. For this purpose, I provide a device, which may appropriately be called a "tripper", comprising a crank 75 fixed to the shaft 13 next to one of the 70 cranks 32 and between the latter and the adjacent leg of the main frame 1, and having pivotally mounted thereon at 76 a pawl 77. A spring 78 coiled about the pivot 76 coacts with the adjacent crank 32 and the 75 pawl 77 and tends to hold the latter in the position shown in Figs. 3 and 4 with a straight edge portion thereof in engagement with a corresponding edge portion of crank 75, and it will be apparent that when pawl 77 is in this position it will be rigid with the crank 75 when pressure is exerted against its upper end in one direction, but will yield or turn about the pivot 76 against the action of spring 78 when pressure is 85 exerted against its said end in the other direction. The tripper is so arranged that when the lift lever 63 is in its lower operative position, as shown in Figs. 6 and 7, the pawl 77 makes contact with the stud 90 or pin 72 of the lift lever both in the return and working strokes of the working pawl 36 and cranks 32. In such return stroke the pawl 77, however, does not act to raise the lift lever 63 for when it engages the 95 pin 72 it merely yields or turns about the pivot 76 and glides past said pin, but in the working stroke it does not yield upon contacting the pin 72 and accordingly acts through the latter to lift and return the 100 lift lever to its normal raised or inoperative position. When the lift lever 63 is thus returned to its normal raised position the working pawl 36 and the retaining pawl 58 immediately move into cooperative 105 relation with the control ratchet 19, and the lift lever 63 will then be held in its said raised position by the engagement of its pin 65 with the upper end 70 of the retaining pawl, until released therefrom, as already 110 described, at the completion of the succeeding actuating stroke of the working pawl.

The indexing mechanism for moving the ratchet governor 20 and control ratchet 19 to their different initial positions or settings to thereby effect the different settings of the machine, is mounted on a plate 80, which is secured as by means of screws, not shown, to the front of the plunger box or numbering wheel head 11. This indexing mechanism, referring to Figs. 1, 2, 11 and 12, comprises a horizontal headed rod or screw 81 which extends through a centrally disposed circular opening in the plate 80 and has a circular disk 82 secured to its inner end as by being in threaded connection therewith, a knob 83 mounted on its outer end,

and a dial 84 and gear 85 mounted thereon between the knob 83 and plate 80. The gear 85 lies adjacent the front face of plate 80, but is spaced slightly therefrom by the cylindrical hub 86 of gear 85, which hub extends outwardly through the central opening in said plate. The dial 84 overlies gear 85, is of larger diameter than the latter, and has an inwardly inclined annular edge portion 87' which serves to effectually hide said gear from view. Threaded on the rod 81 and having its inner end engaging the gear hub 86 is a nut 87 of square or polygonal cross section, and this nut 87 extends through openings in the gear 85 and dial 84 and into a recess in the knob 83, which openings and recess have the same shape in cross-section as the nut. Accordingly, any turning movement of the knob 83 will effect a like turning movement of rod 81, disk 82, gear 85 and dial 84. The plate 80 is provided with a pair of spaced right angular inwardly extending projections 88, 88 which are preferably struck in from the material of the plate and which, with reference to the disk 82, are disposed at diametrically opposite points. Mounted in the projections 88 with its axis parallel to that of shaft 13 and at right angles to the axis of gear 85, is a rod or shaft 89 having mounted on one end thereof a gear 90. The gear 90 projects through the opening 88' of plate 80 produced in the latter by striking in the adjacent projection 88, and meshes with the teeth of gear 85. The teeth of gear 90 also directly mesh with teeth 91 formed in a portion of the outer periphery of the control ratchet governor 20. It will accordingly be apparent that any angular movement of knob 83 will not only effect a like movement of dial 84, disc 82 and gear 85, but will also effect a positive turning movement of the ratchet governor 20. The disc 82 is provided in its outer edge or periphery with a series of spaced notches 93 corresponding in number to the settings for which the machine is designed, there being, of course, nine such notches in the specific form of the machine shown. Reference character 94 represents a lever which is pivotally mounted at one end by a pin 95 on the rear side of the plate 80, and which has its other end disposed in cooperative relation with a short angularly extending portion 58' of the retaining member or pawl 58 which coacts with the control ratchet 19. Intermediate its ends the lever 94 is provided with an upwardly-extending rounded nib 96 engaging the edge of the circular disk 82 and adapted to coact with the notches 93 therein, as will be explained. A strong spring 97 secured at one end to the lever 94 and bearing at its other end against a pin 98 projecting from the plate 80, acts to force the lever upwardly about the pivot

pin 95 and maintain the nib 96 in engagement with the edge of disk 82 under a firm but yielding pressure.

The dial 84 is provided adjacent its edge with a scale comprising suitable indications of the various settings of the machine, and the stationary plate 80 is provided with an indicator in the form of an index mark 99 which cooperates with the said scale. To change the setting of the machine it is merely necessary to move the dial 84 in either direction about its pivotal axis by means of the knob 83 to a position in which that indication of the scale on the dial corresponding to the desired setting registers with the index mark 99 on plate 80. Such movement of the knob 83 and dial 84, as indicated, through the gears 85 and 90 and by reason of the engagement of the latter with the gear teeth 91 of the ratchet governor 20, effects direct positive movement of the governor to the correct angular position for the new setting of the machine. The notched circular disk 82 turns with the knob 83 and dial 84 and the arrangement is such that in any setting of the machine the nib 96 of lever 94 is held, under the action of spring 97, seated in one of the notches 93 of said disk, and the indexing mechanism and ratchet governor 20 are thus firmly but yieldingly locked in proper positions for such setting. In the operation of changing the setting of the machine it is necessary at the beginning of said operation to disengage both the working and retaining pawls 36 and 58 from the control ratchet 19 so as to free the latter and permit the same, in completing such operation, to be moved with the ratchet governor 20 through the resilient connection 22 to the proper initial position for the new setting. This disengagement of the pawls 36 and 58 is automatically effected by the coaction of lever 94 with the retaining pawl 58, for when the disk 82 is turned sufficiently to effect disengagement of any notch 93 thereof and the nib 96 of lever 94, the latter is forced downwardly against the action of spring 97 so as to cause said nib to ride on a high circular edge portion of the disk between said notch and an adjacent notch 93; and in such downward movement of the lever the free end thereof engages the angular projection 58' of the retaining pawl and thereby moves the latter outwardly about the pivot pin 59 and against the action of spring 61 to a position in which the tooth 60 of this pawl is out of the path of the ratchet teeth 56 and 57, while in such outward movement of the pawl 58 the curved end 70 thereof is moved clear of the pin 65 of the lift lever 63 and the latter drops under the action of the spring 69 to a position corresponding to that shown in Figs. 6 and 7, and disengages the working pawl 36 from the notched inner periphery of the control

ratchet. The lift lever 63 remains in this lowered position after the completion of the operation of changing the setting of the machine and thereby holds the working and retaining pawls 36 and 58 disengaged from the control ratchet 19, until restored to its normal raised and inoperative position as described above, upon the next working stroke of the pawl 36. This next working stroke of pawl 36 is, of course, the first working stroke thereof in the new setting of the machine. It will thus be seen that merely by resetting the dial 84, the control mechanism will be reindexed directly and the control ratchet automatically reset in the proper initial position for the beginning of the new setting. All errors such as frequently occur in numbering machines after reindexing or resetting, are entirely eliminated with my improved construction since the control ratchet will always become operative at the beginning of its new initial position or setting, and this is true regardless of whether the control ratchet is moved to such new initial position or setting either before the number then set up on the type wheels has been printed the predetermined number of times conforming to the preceding setting or at the completion of such a predetermined number of printings.

In a numbering machine constructed in accordance with my invention wear and interference of the parts are reduced to a minimum. In this connection it is to be noted that in the consecutive setting of the machine there is no wear or interference whatever of the parts of the control mechanism as the latter is then inoperative; and that in the repeat setting the control ratchet acts directly on the working pawl to hold the latter disengaged from the numbering wheels and the control mechanism is otherwise entirely inoperative, whereby wear and interference are again eliminated.

The machine is preferably provided with suitable pawl retaining means (not shown), such, for example, as that employed in the structure described in my prior Patent 1,474,715 above referred to, adapted to coact with the notched inner peripheries of the numbering or type wheels to prevent rearward movement of these wheels and also to prevent said wheels from being too easily advanced.

As hereinbefore indicated the principles of my invention are not limited to numbering machines of the character specifically described herein, but are applicable to practically all other types of automatic numbering machines. It is also to be understood that the specific embodiment of my invention shown and described herein is subject to numerous modification in the size, shape and arrangement of parts without de-

parture from the spirit of my invention or 65 the scope of the appended claims.

Having now described my invention, what I claim as new and desire to protect by Letters Patent is as follows:

1. In a numbering machine, a main frame, 70 a head mounted for reciprocatory movement in said main frame and carrying a series of type wheels, pawl means having a plurality of pawls respectively coacting with and adapted to actuate said wheels, means for 75 operating said pawl means upon reciprocatory movement of said head in the main frame, and mechanism for controlling the actuation of the pawl means by said operating means comprising a device movable 80 with at least one of said pawls and a single control member adapted to coact directly with said device and also adapted to be set in a plurality of different initial positions and thereby effect a corresponding number 85 of different settings of the machine.

2. In a numbering machine, a main frame, 90 a head mounted for reciprocatory movement in said main frame and carrying a series of type wheels, pawl means adapted to actuate 95 said wheels, means for operating said pawl means upon reciprocatory movement of said head in the main frame, mechanism for controlling the pawl means comprising a single control member adapted to coact directly 95 with said pawl means and adapted to be set in a plurality of different initial positions and thereby effect a corresponding number of different settings of the machine, and means for setting said control member in its 100 various initial positions comprising a governor member having a resilient connection with the control member, said connection providing for movement of the control member relatively to the governor member by 105 said pawl means.

3. In a numbering machine, a main frame, 110 a head mounted for reciprocatory movement in said main frame and carrying a series of type wheels, pawl means adapted to actuate 115 said wheels, means for operating said pawl means upon reciprocatory movement of said head in the main frame, mechanism for controlling the pawl means comprising a single control member adapted to coact directly 115 with said pawl means and adapted to be set in a plurality of different initial positions and thereby effect a corresponding number of different settings of the machine, and means for setting said control member in its 120 various initial positions comprising a governor member having a resilient connection with the control member and indexing mechanism for actuating said governor member, said connection providing for movement of the control member relatively to the governor member by 125 said pawl means.

4. In a numbering machine, a main frame,

- a head mounted for reciprocatory movement in said main frame and carrying a series of type wheels, pawl means adapted to actuate said wheels, means for operating said pawl means upon reciprocatory movement of said head in the main frame, mechanism for controlling the pawl means comprising a single control member adapted to coact directly with said pawl means and adapted to be set with said pawl means and adapted to be set in a plurality of different initial positions and thereby effect a corresponding number of different settings of the machine, and means for setting said control member in its various initial positions comprising a governor member having a resilient connection with the control member and indexing mechanism for actuating said governor member, said indexing mechanism having means for yieldingly locking the governor member in a plurality of different positions corresponding to the different settings of the machine.
5. In a numbering machine, a main frame, a head mounted for reciprocatory movement in said main frame and carrying a series of type wheels, pawl means adapted to actuate said wheels, means for operating said pawl means upon reciprocatory movement of said head in the main frame, and mechanism for controlling the actuation of the type wheels by said pawl means comprising a control member adapted to coact directly with said pawl means and adapted to be set in a plurality of different initial positions to thereby effect a corresponding number of different settings of the machine and resilient means tending to hold said control member in any initial position in which it may be set, said control member having a series of spaced notches with which the pawl means, when operated, coacts to impart to the control member a step-by-step movement in opposition to the action thereon of said resilient means.
6. In a numbering machine, a main frame, a head mounted for reciprocatory movement in said main frame, a series of type wheels coaxially mounted on said head, pawl means adapted to actuate said wheels, means for operating said pawl means upon reciprocatory movement of said head in the main frame, and mechanism for controlling the actuation of the type wheels by said pawl means comprising a control member mounted on said head coaxially with said wheels for turning movement, said control member being adapted to coact directly with said pawl means and being adapted to be set in a plurality of different initial positions to thereby effect a corresponding number of different settings of the machine.
7. In a numbering machine, a series of type wheels, pawl means having a plurality of pawls respectively coacting with and adapted to actuate said wheels, means for operating said pawl means, and mechanism for controlling the actuation of the type wheels by said pawl means comprising a device movable with one at least of said pawls and a control member adapted to coact directly with said device and adapted to be set in a plurality of different initial positions to thereby effect a corresponding number of different settings of the machine.
8. In a numbering machine, a series of type wheels, pawl means having a plurality of pawls respectively coacting with and adapted to actuate said wheels, means for operating said pawl means, and mechanism for controlling the actuation of the type wheels by said pawl means comprising a device movable with one at least of said pawls and a control member adapted to coact directly with said device and adapted to be set in a plurality of different initial positions to thereby effect a corresponding number of different settings of the machine, said control member being provided with means with which said device is adapted to directly coact upon the operation of the latter to effect movement of such control member away from any such initial position in which it may be set.
9. In a numbering machine, a series of type wheels, pawl means having a plurality of pawls respectively coacting with and adapted to actuate said wheels, means for operating said pawl means, and mechanism for controlling the actuation of the type wheels by said pawl means comprising a device movable with one at least of said pawls and a control member adapted to coact directly with said device and adapted to be set in a plurality of different initial positions to thereby effect a corresponding number of different settings of the machine, said control member being provided with means with which said device is adapted to directly coact upon the operation of the latter to effect step-by-step movement of such control member away from any such initial position in which it may be set.
10. In a numbering machine, a series of type wheels, pawl means adapted to actuate said wheels, means for effecting operation of said pawl means, mechanism for controlling the actuation of the type wheels by said pawl means comprising a control member adapted to coact directly with said pawl means and adapted to be set in a plurality of different initial positions to thereby effect a corresponding number of different settings of the machine, said control member being provided with means with which said pawl means is adapted to directly coact upon the operation of the latter to effect movement of such control member away from any such initial position in which it may be set, and mechanism for setting said control member in its initial positions comprising resilient means which acts to op-

pose such movement of said control member from any initial position thereof.

11. In a numbering machine, a series of type wheels, means for advancing said wheels including a pawl device, having a plurality of pawls respectively coacting with said wheels and a member movable with at least one of such pawls and control mechanism for said pawl device adjustable to effect a plurality of settings of the machine other than the "repeat" and "consecutive" settings thereof, said mechanism including a rotatably mounted element arranged so that in each such other setting of the machine it is actuatable directly by said member and is also adapted to control said pawl device.

12. In a numbering machine, a series of coaxially mounted type wheels, means for advancing said wheels including a pawl device, comprising a plurality of relatively fixed pawls and control mechanism for said pawl device adjustable to effect a plurality of settings of the machine other than the "repeat" and "consecutive" settings thereof, said mechanism including a member rotatably mounted adjacent to and coaxially with said type wheels and being so arranged that in any such other setting of the machine it is actuatable by one of said pawls upon operation of the machine and is also adapted to control the pawl device.

13. In a numbering machine, a series of type wheels, means for advancing said wheels including a pawl device, having a plurality of relatively fixed pawls and control mechanism adjustable to effect a plurality of settings of the machine, said mechanism including a rotatable member mounted adjacent to and coaxially with said type wheels and adapted to be actuated by one of said pawls and also to control said pawl device in each of the settings of the machine.

14. In a numbering machine, a series of type wheels, an oscillatory pawl device for advancing said wheels, indexing mechanism comprising an indicating member movable to effect the various settings of the machine, and a ratchet member for controlling the coaction of said pawl device with the type wheels and having a resilient connection with said indexing mechanism, said pawl device being adapted in successive complete oscillatory movements thereof and in certain settings of the machine, to directly impart to said ratchet member a step-by-step movement in opposition to the action thereon of said resilient connection.

15. In a numbering machine, a series of type wheels, an oscillatory pawl device for advancing said wheels, means comprising a ratchet for controlling the coaction of said pawl device with said type wheels, mechanism having a resilient connection with said ratchet for moving the latter to different ini-

itial positions and adapted to thereby effect the different settings of the machine, said ratchet being adapted when in a predetermined position to permit the pawl device to coact with said wheels and when in any other position to prevent the pawl device from coacting with the type wheels, the pawl device in a certain setting of the machine being adapted, when oscillated, to impart a step-by-step movement to said ratchet away from its corresponding initial position and against the action of said resilient connection towards said predetermined position, a device coacting with the ratchet for holding the latter after each such step movement thereof, and means adapted when the ratchet reaches such predetermined position to automatically effect the release of the ratchet from said holding device and the pawl device and thereby permit said resilient connection to return the ratchet to its said corresponding initial position.

16. In a numbering machine, a series of type wheels, an oscillatory pawl device for advancing said wheels, means comprising a ratchet for controlling the coaction of said pawl device with said type wheels, mechanism having a resilient connection with said ratchet for moving the latter to different initial positions and adapted to thereby effect the different settings of the machine, said ratchet being adapted when in a predetermined position to permit the pawl device to coact with said wheels and when in any other position to prevent the pawl device from coacting with the type wheels, the pawl device in a certain setting of the machine being adapted, when oscillated, to impart a step-by-step movement to said ratchet away from its corresponding initial position and against the action of said resilient connection towards said predetermined position, a device coacting with the ratchet for holding the latter after each such step movement thereof, and means controlled by the ratchet and adapted when the latter reaches such predetermined position to automatically effect the release of the ratchet from said holding device and the pawl device and thereby permit said resilient connection to return the ratchet to its said corresponding initial position.

17. In a numbering machine, a series of type wheels, pawl means adapted to actuate said wheels, means for operating said pawl means, and mechanism for controlling the actuation of the type wheels by said pawl means comprising a control member adapted to coact directly with said pawl means and adapted to be set in a plurality of different initial positions to thereby effect a corresponding number of different settings of the machine, said control member having means formed integrally therewith and with which said pawl means is adapted to directly coact upon the operation of the latter to effect

movement of such control member away from any such initial position in which it may be set, and means adapted in any such setting of the machine and after a predetermined movement of the control member from its corresponding initial position, to automatically effect the return of the control member to such initial position.

18. In a numbering machine, a series of type wheels, pawl means adapted to actuate said wheels, means for operating said pawl means, and mechanism for controlling the actuation of the type wheels by said pawl means comprising a control member adapted to coat directly with said pawl means and adapted to be set in a plurality of different initial positions to thereby effect a corresponding number of different settings of the machine, said control member having means formed integrally therewith and with which said pawl means is adapted to directly coat upon the operation of the latter to effect movement of such control member away from any such initial position in which it may be set, and means controlled by said control member and adapted in any such setting of the machine and after a predetermined movement of the control member from its corresponding initial position, to automatically effect the return of the control member to such initial position.

19. In a numbering machine, a series of type wheels, means for advancing said wheels including a device consisting of a plurality of relatively fixed pawls, and control mechanism for said device adjustable to effect a plurality of settings of the machine in addition to the "repeat" and "consecutive" settings thereof, said mechanism including a rotatably mounted member arranged so that in each of such additional settings of the machine it is actuatable directly by one of said pawls and is also adapted to control said device.

45 20. In a machine of the character described, a series of type wheels, means for advancing said wheels including a device consisting of a plurality of relatively fixed pawls, and control mechanism for said device adjustable to effect a plurality of settings of the machine in addition to the "repeat" and "consecutive" settings thereof, said mechanism including a rotatably mounted member arranged so that in each of such additional settings of the machine it is actuatable directly by one of said pawls and is also adapted to control said device, said member in the "repeat" setting of the machine being continuously in engagement with said device to maintain the latter out of coacting relation with the type wheels.

21. In a machine of the character described, a series of type wheels, means for advancing said wheels including a pawl device, and control mechanism for said pawl

device adjustable to effect a plurality of settings of the machine in addition to the "repeat" and "consecutive" settings thereof, said mechanism including a rotatably mounted member arranged so that in each of such additional settings of the machine it is actuatable directly by said pawl device and is also adapted to control the latter, said member having a cutaway portion which in the "consecutive" setting of the machine, is positioned to permit the pawl device continuously to be in coactive relation with the type wheels.

22. In a machine of the character described, a series of type wheels, means for advancing said wheels including a pawl device, and control mechanism for said pawl device adjustable to effect a plurality of settings of the machine in addition to the "repeat" and "consecutive" settings thereof, said mechanism including a rotatably mounted member arranged so that in each of such additional settings of the machine it is actuatable directly by said pawl device and is also adapted to control the latter, said member in the "repeat" setting of the machine being continuously in engagement with the pawl device to maintain the latter out of coacting relation with the type wheels, and said member having a cutaway portion which in the "consecutive" setting of the machine, is positioned to permit the pawl device continuously to be in coactive relation with the type wheels.

23. In a numbering machine, a series of type wheels, type wheel advancing means including a working pawl, indexing mechanism movable to effect different settings of the machine, a control member yieldingly movable with said mechanism, and means for holding said mechanism in various positions corresponding respectively to said settings, the pawl being adapted upon each of successive actuations thereof in certain settings of the machine directly to actuate and move the control member while being itself held by the control member from coacting with the type wheels.

24. In a numbering machine, a series of type wheels, type wheel advancing means including a working pawl, indexing mechanism movable to effect different settings of the machine, a control member yieldingly movable with said mechanism, and means for holding said mechanism in various positions corresponding respectively to said settings, the pawl being adapted upon each of successive actuations thereof in certain settings of the machine directly to actuate and move the control member while being itself held by the control member from coacting with the type wheels, and the pawl being movable into coacting relation with the type wheels when the control member reaches a predetermined point in its travel.

25. In a numbering machine, a series of type wheels, type wheel advancing means including a working pawl, indexing mechanism movable to effect different settings of the machine, a control member yieldingly movable with said mechanism, and means for holding said mechanism in various positions corresponding respectively to said settings, the pawl being adapted upon each of successive actuations thereof in certain settings of the machine directly to actuate and move the control member while being itself held by the control member from coacting with the type wheels, and the pawl being movable into coacting relation with the type wheels when the control member reaches a predetermined point in its travel determined by the extent of movement of the indexing mechanism.
- 20 26. In a numbering machine, a series of type wheels, type wheel advancing means including a working pawl, indexing mechanism movable to effect different settings of the machine, a control member yieldingly movable with said mechanism, and means for holding said mechanism in various positions corresponding respectively to said settings, the pawl being adapted upon each of successive actuations thereof in certain settings of the machine directly to actuate and move the control member while being itself held by the control member from coacting with the type wheels, the type wheel actuating function of the pawl being automatically restored when the control member reaches a predetermined point in its travel determined by the extent of the movement of the control member in unison with that of the indexing mechanism.
- 25 27. In a machine of the class described, a series of type wheels, type wheel advancing mechanism including a working pawl, indexing mechanism movable to effect different settings of the machine, a ratchet wheel yieldably movable with said mechanism, means for holding said mechanism in various positions corresponding respectively to said settings, the pawl being adapted upon each of successive actuations thereof in certain settings of the machine directly to actuate and advance the ratchet wheel while being itself held by the latter from coacting with the type wheels, a retaining pawl coacting with the teeth of the ratchet wheel to hold the latter after each advance movement thereof, the type wheel actuating function of the pawl being automatically restored after a predetermined advance movement of the ratchet wheel determined by the extent of the movement of the ratchet wheel in unison with that of the indexing mechanism, and means adapted after such predetermined advance movement of the ratchet wheel automatically to release the retaining pawl and effect the return of the ratchet wheel to its normal position with respect to the indexing mechanism.
- 30 28. In a machine of the class described, a series of type wheels, type wheel advancing mechanism including a working pawl, indexing mechanism movable to effect different settings of the machine, a ratchet wheel yieldably movable with said mechanism, means for holding said mechanism in various positions corresponding respectively to said settings, the pawl being adapted upon each of successive actuations thereof in certain settings of the machine directly to actuate and advance the ratchet wheel while being itself held by the latter from coacting with the type wheels, a retaining pawl coacting with the teeth of the ratchet wheel to hold the latter after each advance movement thereof, the type wheel actuating function of the pawl being automatically restored after a predetermined advance movement of the ratchet wheel determined by the extent of the movement of the ratchet wheel in unison with that of the indexing mechanism, and means comprising one of the teeth of the ratchet wheel adapted after such predetermined advance movement of the ratchet wheel automatically to release the retaining pawl and effect the return of the ratchet wheel to its normal position with respect to the indexing mechanism.
- 35 29. In a numbering machine, a series of type wheels, type wheel advancing mechanism including a pawl device, indexing mechanism, means for holding said mechanism in any position in which it is set, a ratchet for controlling said pawl device and having a resilient connection with said mechanism, said pawl device being adapted upon successive actuations thereof directly to advance said ratchet step by step against the action of said resilient connection, a retaining pawl for preventing backward movement of the ratchet, and means for releasing the retaining pawl to thereby automatically effect the return of the ratchet to its normal position with respect to the indexing mechanism.
- 40 30. In a numbering machine, a series of type wheels, type wheel advancing mechanism including a pawl device, indexing mechanism, means for holding said mechanism in any position in which it is set, a ratchet for controlling said pawl device and having a resilient connection with said mechanism, said pawl device being adapted upon successive actuations thereof directly to advance said ratchet step by step against the action of said resilient connection, a retaining pawl for preventing backward movement of the ratchet, and means carried by the ratchet for releasing the retaining pawl to thereby automatically effect the return of the ratchet to its normal position with respect to the indexing mechanism.

31. In a numbering machine, a series of type wheels, type wheel advancing mechanism including a pawl device, indexing mechanism, means for holding said mechanism in any position in which it is set, a ratchet for controlling said pawl device and having a resilient connection with said mechanism, said pawl device being adapted upon successive actuations thereof directly to advance said ratchet step by step against the action of said resilient connection, a retaining pawl for preventing backward movement of the ratchet, means for releasing the retaining pawl to thereby automatically effect the return of the ratchet to its normal position with respect to the indexing mechanism, and means for effecting the return of the retaining pawl to its operative position.
32. In a numbering machine, a series of type wheels, type wheel advancing mechanism including a pawl device, indexing mechanism, means for holding said mechanism in any position in which it is set, a ratchet for controlling said pawl device and having a resilient connection with said mechanism, said pawl device being adapted upon successive actuations thereof directly to advance said ratchet step by step against the action of said resilient connection, a retaining pawl for preventing backward movement of the ratchet, means for releasing the retaining pawl to thereby automatically effect the return of the ratchet to its normal position with respect to the indexing mechanism, and means for effecting automatically the return of the retaining pawl to its operative position upon the succeeding actuation of said pawl device.
33. In a numbering machine, a series of type wheels, type wheel advancing mechanism including a pawl device, indexing mechanism, means for holding said mechanism in any position in which it is set, a ratchet for controlling said pawl device and having a series of teeth and a resilient connection with said mechanism, said pawl device being adapted upon successive actuations thereof directly to advance said ratchet step by step against the action of said resilient connection, a retaining pawl coacting with said series of teeth for preventing backward movement of the ratchet, and means comprising a high tooth provided on the ratchet at one end of said series of teeth for releasing the retaining pawl to thereby automatically effect the return of the ratchet to its normal position with respect to the indexing mechanism.
34. In a numbering machine, a series of type wheels, type wheel advancing mechanism including a pawl device, indexing mechanism, means for holding said mechanism in any setting thereof, a ratchet for controlling said pawl device and having a resilient connection with said mechanism, said ratchet being provided with two series of teeth, the pawl device being adapted upon successive actuations thereof directly to coact with one of said series of teeth and thereby advance the ratchet step by step against the action of said resilient connection, a retaining pawl coacting with the other of said series of teeth for preventing backward movement of the ratchet, and means adapted to effect movement of said retaining pawl and pawl device to inoperative positions with respect to the respective series of teeth of the ratchet and thereby effect the return of the ratchet to its normal position with respect to the indexing mechanism.
35. In a numbering machine, a series of type wheels, type wheel advancing mechanism including a pawl device, indexing mechanism, means for holding said mechanism in any setting thereof, a ratchet for controlling said pawl device and having a resilient connection with said mechanism, said pawl device being adapted upon successive actuations thereof directly to advance said ratchet step by step against the action of said resilient connection, a retaining pawl for preventing backward movement of the ratchet, and means for effecting the movement of both the pawl device and the retaining pawl to inoperative positions with respect to the ratchet to thereby effect the return of the latter to its normal position with respect to the indexing mechanism.
36. In a numbering machine, a series of type wheels, type wheel advancing mechanism including a pawl device, indexing mechanism, means for holding said mechanism in any setting thereof, a ratchet for controlling said pawl device and having a resilient connection with said mechanism, said pawl device being adapted upon successive actuations thereof directly to advance said ratchet step by step against the action of said resilient connection, a retaining pawl for preventing backward movement of the ratchet and means comprising a member carried by the ratchet for effecting the movement of both the pawl device and the retaining pawl to inoperative positions with respect to the ratchet to thereby effect the return of the latter to its normal position with respect to the indexing mechanism.
37. In a numbering machine, a series of type wheels, type wheel advancing mechanism including a pawl device, indexing mechanism, means for holding said mechanism in any setting thereof, a ratchet for controlling said pawl device and having a resilient connection with said mechanism, said pawl device being adapted upon successive actuations thereof directly to advance said ratchet step by step against the action of said resilient connection, a retain-

- ing pawl for preventing backward movement of the ratchet, and means adapted after a predetermined advance movement of the ratchet automatically to effect the movement of both the pawl device and the retaining pawl to inoperative positions with respect to the ratchet to thereby effect the return of the latter to its normal position with respect to the indexing mechanism.
38. In a numbering machine, a series of type wheels, type wheel advancing mechanism including a pawl device, indexing mechanism, means for holding said mechanism in any setting thereof, a ratchet for controlling said pawl device and having a resilient connection with said mechanism, said pawl device being adapted upon successive actuations thereof directly to advance said ratchet step by step against the action of said resilient connection, a retaining pawl for preventing backward movement of the ratchet, and means adapted after a predetermined advance movement of the ratchet, determined by the extent of the movement of the ratchet in unison with that of the indexing mechanism, automatically to effect the movement of both the pawl device and the retaining pawl to inoperative positions with respect to the ratchet to thereby effect the return of the latter to its normal position with respect to the indexing mechanism.
39. In a numbering machine, a series of type wheels, type wheel advancing mechanism including a pawl device, indexing mechanism, means for holding said mechanism in any setting thereof, a ratchet for controlling said pawl device and having a resilient connection with said mechanism, said pawl device being adapted upon successive actuations thereof directly to advance said ratchet step by step against the action of said resilient connection, a retaining pawl for preventing backward movement of the ratchet, means adapted after a predetermined advance movement of the ratchet automatically to effect the movement of both the pawl device and the retaining pawl to inoperative positions with respect to the ratchet to thereby effect the return of the latter to its normal position with respect to the indexing mechanism, and means operable upon the following actuation of the machine to effect the return of the pawl device and the retaining pawl to their operative positions with respect to the ratchet.
40. In a numbering machine, a series of type wheels, type wheel advancing mechanism including a pawl device, indexing mechanism, means for holding said mechanism in any setting thereof, a ratchet for controlling said pawl device and having a resilient connection with said mechanism, said pawl device being adapted upon suc-

cessive actuations thereof directly to advance said ratchet step by step against the action of said resilient connection, a retaining pawl for preventing backward movement of the ratchet, and means rendered operable by movement of the indexing mechanism from any setting thereof to effect the movement of both the pawl device and the retaining pawl to inoperative positions with respect to the ratchet to thereby effect the return of the latter to its normal position with respect to the indexing mechanism.

41. In a numbering machine, a series of type wheels, type wheel advancing mechanism including a pawl device, indexing mechanism, means for holding said mechanism in any setting thereof, a ratchet for controlling said pawl device and having a resilient connection with said mechanism, said pawl device being adapted upon successive actuations thereof directly to advance said ratchet step by step against the action of said resilient connection, a retaining pawl for preventing backward movement of the ratchet, and means comprising part of the means for holding the indexing mechanism adapted to effect the movement of both the pawl device and the retaining pawl to inoperative positions with respect to the ratchet to thereby effect the return of the latter to its normal position with respect to the indexing mechanism.

42. In a numbering machine, a series of type wheels, type wheel advancing mechanism including a pawl device, indexing mechanism, means for holding said mechanism in any setting thereof, a ratchet for controlling said pawl device and having a resilient connection with said mechanism, said pawl device being adapted upon successive actuations thereof directly to advance said ratchet step by step against the action of said resilient connection, a retaining pawl for preventing backward movement of the ratchet, and means comprising part of the means for holding the indexing mechanism adapted when moved from its holding position to effect the movement of both the pawl device and the retaining pawl to inoperative positions with respect to the ratchet to thereby effect the return of the latter to its normal position with respect to the indexing mechanism.

43. In a numbering machine, a series of type wheels, type wheel advancing mechanism including a pawl device, indexing mechanism, means for holding said mechanism in any setting thereof, a ratchet for controlling said pawl device and having a resilient connection with said mechanism, said pawl device being adapted upon successive actuations thereof directly to advance said ratchet step by step against the action of said resilient connection, a retaining pawl

for preventing backward movement of the ratchet, means rendered operable by movement of the indexing mechanism from any setting thereof to effect the movement of both the pawl device and the retaining pawl to inoperative positions with respect to the ratchet to thereby effect the return of the latter to its normal position with respect to the indexing mechanism, and means operable upon the following actuation of the machine to effect the return of the pawl device and the retaining pawl to their operative positions with respect to the ratchet.

44. In a numbering machine, a series of type wheels, type wheel advancing mechanism including a pawl device, indexing mechanism, means for holding such mechanism in any setting thereof, a ratchet for controlling said pawl device and having a resilient connection with said mechanism, said pawl device being adapted upon successive actuations thereof directly to advance said ratchet step by step against the action of said resilient connection, a retaining pawl for preventing backward movement of the ratchet, means comprising part of the means for holding the indexing mechanism adapted when moved from its holding position to effect the movement of both the pawl device and the retaining pawl to inoperative positions with respect to the ratchet to thereby effect the return of the latter to its normal position with respect to the indexing mechanism, and means operable upon the following actuation of the machine to effect the return of the pawl device and the retaining pawl to their operative positions with respect to the ratchet.

45. In a numbering machine, a series of type wheels, means including a pawl device for advancing said wheels, indexing mechanism, means for holding said mechanism in any setting thereof, a ratchet for controlling the pawl device, a spring connecting the ratchet and said mechanism, said pawl device being adapted upon successive actuations thereof directly to engage and advance said ratchet against the action of said spring, and a member adapted to prevent backward movement of said ratchet under the action of said spring.

46. In a numbering machine, a series of type wheels, means including a pawl device for advancing said wheels, indexing mechanism, means for holding said mechanism in any setting thereof, a ratchet for controlling the pawl device, a spring connecting the ratchet and said mechanism, said pawl device being adapted upon successive actuations thereof directly to engage and advance said ratchet against the action of said spring, a member adapted to prevent backward movement of said ratchet under the action of said spring, and means carried by said ratchet adapted to contact said member and

move it to inoperative position with respect to the ratchet.

47. In a numbering machine, a series of type wheels, means including a pawl device for advancing said wheels, indexing mechanism, means for holding said mechanism in any setting thereof, a ratchet for controlling the pawl device, a spring connecting the ratchet and said mechanism, said pawl device being adapted upon successive actuations thereof directly to engage and advance said ratchet against the action of said spring, a member adapted to prevent backward movement of said ratchet under the action of said spring, means carried by said ratchet adapted to contact said member and move it to inoperative position with respect to the ratchet, and means movable with the pawl device and adapted upon the following actuation of the latter automatically to effect the return of said member to operative position with respect to the ratchet.

48. In a machine of the class described, a series of numbering wheels, means including a pawl device adapted upon each actuation thereof normally to advance said wheels one unit, and means whereby a number set up on said wheels may be automatically repeated a predetermined number of times and the number of such predeterminations varied and the original number set up on the wheels repeated after such variation, including an adjustable indicating member, a governor member connected thereto so as to be set to position therewith, a control member, said governor and control members being provided with cooperating stops, a resilient connection between the governor member and control member tending to maintain the same in given relative positions with said stops in engagement, said control member being adapted to be moved directly by said pawl device on each actuation of the latter against the action of said resilient connection, and means adapted to limit such movement of the control member to an extent corresponding to the number at which said indicating member is set and to then effect the return of such control member to the position in which the stop thereof engages the stop of said governor member.

49. In a machine of the class described, a series of numbering wheels, means including a pawl device adapted upon each actuation thereof normally to advance said wheels one unit, and means whereby a number set up on said wheels may be automatically repeated any predetermined number of times at will and the number of such predeterminations varied before the original number of predeterminations has been completed, including an adjustable indicating member, a governor member connected thereto so as to be set to position therewith, a control member, said governor and control members be-

ing provided with cooperating stops, a resilient connection between the governor member and control member tending to maintain the same in given relative positions with said stops in engagement, said control member being adapted to be moved directly by said pawl device on each actuation of the latter against the action of said resilient connection, and means adapted to limit such movement of the control member to an extent corresponding to the number at which said indicating member is set and to then effect the return of such control member to the position in which the stop thereof engages the stop of said governor member.

50. In a machine of the class described, a series of numbering wheels, means including a pawl device adapted upon each actuation thereof normally to advance said wheels one unit, and means whereby a number set up on said wheels may be automatically repeated a predetermined number of times, automatically advanced one unit and automatically repeated the same predetermined 25 number of times, and whereby the number of either of such predeterminations may be varied before they have been completed, including an adjustable indicating member, a governor member connected thereto so as 30 to be set to position therewith, a control member, said governor and control members being provided with cooperating stops, a resilient connection between the governor member and control member tending to 35 maintain the same in given relative positions with said stops in engagement, said control member being adapted to be moved directly by said pawl device on each actuation of the latter against the action of said resilient connection, and means adapted to limit such 40 movement of the control member to an extent corresponding to the number at which said indicating member is set and to then effect the return of such control member to the position in which the stop thereof engages the stop of said governor member.

51. In a numbering machine, a series of type wheels, type wheel advancing means comprising a pawl device, means for controlling the pawl device comprising a control member adapted to coact directly with the pawl device, and means for setting said control member in a plurality of different initial positions to thereby effect a corresponding number of different settings of the machine comprising a governor member having a resilient connection with the control member, movable indicating means, and a member movable with said indicating means and having a direct geared connection with said governor member.

52. In a numbering machine, a series of type wheels, type wheel advancing means comprising a pawl device, means for controlling the pawl device comprising a con-

trol member adapted to coact directly with the pawl device, and means for setting said control member in a plurality of different initial positions to thereby effect a corresponding number of different settings of the machine comprising a governor member having a resilient connection with the control member, movable indicating means, and a member movable with said indicating means and having a direct geared connection with said member, the said control and governor members being mounted adjacent each other for movement about a common axis and having cooperative stops, and said resilient connection constantly tending to maintain the control member in a position relative to the governor member in which said stops are in engagement.

53. In a numbering machine, a series of type wheels, type wheel advancing means, means for controlling said advancing means, and means for setting said controlling means in a number of different initial positions to thereby effect a corresponding number of different settings of the machine comprising a rotatable governor member having a resilient connection with the controlling means and provided with gear teeth, movable indicating means, and a gear movable by said indicating means about an axis substantially at right angles to the axis of rotation of the governor member and having its teeth meshing with the gear teeth of the governor member.

54. In a numbering machine, a series of 100 annular type wheels, an annular control member adjacent the type wheels, and type wheel advancing means comprising a pawl member mounted within and adapted to coact with both the type wheels and the 105 control member, in a plurality of different settings of the machine.

55. In a numbering machine, a series of annular type wheels, an annular control member adjacent the type wheels, type 110 wheel advancing means comprising a pawl member mounted within and adapted to coact with both the type wheels and the control member, in a plurality of different settings of the machine, and means for setting said control member in a plurality of different initial positions to thereby effect a corresponding number of different settings of the machine comprising a member having a resilient connection with the control member.

56. In a numbering machine, a series of annular type wheels, an annular control member adjacent the type wheels, type 115 wheel advancing means comprising a pawl member mounted within and adapted to coact with both the type wheels and the control member, in a plurality of different settings of the machine, and means for setting said control member in a plurality of 120

different initial positions to thereby effect a corresponding number of different settings of the machine comprising a member having a resilient connection with the control member, said control member being provided on its inner periphery with a series of spaced notches with which said pawl member upon successive actuations thereof, is adapted to coact to advance the control member step by step against the action of said resilient connection.

57. In a numbering machine, a series of annular type wheels, an annular control member adjacent the type wheels, and type wheel advancing means comprising an oscillatory pawl member mounted within and adapted to coact with both the type wheels and the control member, in a plurality of different settings of the machine, said pawl member being immovable in the direction of the axes of the type wheels and control member.

58. In a numbering machine, a series of annular type wheels, an annular control member adjacent the type wheels, type wheel advancing means comprising a pawl member mounted within and adapted to coact with both the type wheels and the control member in a plurality of different settings of the machine, and means for setting said control member in a plurality of different initial positions to thereby effect a corresponding number of different settings of the machine comprising a member having a resilient connection with the control member, said control member having a section of its inner periphery provided with a series of spaced shallow notches and a deep notch or recess adjacent one end of such series, the said deep 40 notch in a predetermined position of the control member, being adapted to permit the pawl member to coact with the type wheels, and the pawl member upon successive actuations thereof being adapted to coact with the said series of shallow notches to advance the control member step by step against the action of said resilient connection towards said predetermined position.

59. In a numbering machine, a series of type wheels, type wheel advancing means including a pawl device, controlling means for the pawl device comprising a ratchet wheel, indexing mechanism having a resilient connection with said ratchet wheel, means for holding the indexing mechanism in any setting thereof, the pawl device being adapted upon each of successive actuations thereof to advance the ratchet wheel against the action of said resilient connection, a retaining pawl coacting with the ratchet wheel to prevent backward movement thereof under the action of said resilient connection, a member movable to a position to engage and hold the pawl device out of cooperative position with respect to the

ratchet wheel, said member normally being held by the retaining pawl in inoperative position, and means adapted to move the retaining pawl to inoperative position and to thereby effect the movement of said member to its operative position, whereupon the ratchet wheel will be released and returned to its original position.

60. In a numbering machine, a series of type wheels, type wheel advancing means including a pawl device, controlling means for the pawl device comprising a ratchet wheel, indexing mechanism having a resilient connection with said ratchet wheel, means for holding the indexing mechanism in any setting thereof, the pawl device being adapted upon each of successive actuations thereof to advance the ratchet wheel against the action of said resilient connection, a retaining pawl coacting with the ratchet wheel to prevent backward movement thereof under the action of said resilient connection, a member movable to a position to engage and hold the pawl device out of cooperative position with respect to the ratchet wheel, said member normally being held by the retaining pawl in inoperative position, and means carried by the ratchet wheel and adapted when the latter reaches a predetermined point in its advance movement, to move the retaining pawl to inoperative position and to thereby effect the movement of said member to its operative position, whereupon the ratchet wheel will be released and returned to its original position.

61. In a numbering machine, a series of type wheels, type wheel advancing means including a pawl device, controlling means for the pawl device comprising a ratchet wheel, indexing mechanism having a resilient connection with said ratchet wheel, means for holding the indexing mechanism in any setting thereof, the pawl device being adapted upon each of successive actuations thereof to advance the ratchet wheel against the action of said resilient connection, a retaining pawl coacting with the ratchet wheel to prevent backward movement thereof under the action of said resilient connection, a member movable to a position to engage and hold the pawl device out of cooperative position with respect to the ratchet wheel, said member normally being held by the retaining pawl in inoperative position, and means operated upon movement of the indexing mechanism in effecting a change of the machine setting, to move the retaining pawl to inoperative position and to thereby effect the movement of said member to its operative position, whereupon the ratchet wheel will be released and returned to its original position.

62. In a numbering machine, a series of type wheels, type wheel advancing means in-

cluding a pawl device, controlling means for the pawl device comprising a ratchet wheel, indexing mechanism having a resilient connection with said ratchet wheel, means for holding the indexing mechanism in any setting thereof, the pawl device being adapted upon each of successive actuations thereof to advance the ratchet wheel against the action of said resilient connection, a retaining pawl coating with the ratchet wheel to prevent backward movement thereof under the action of said resilient connection, a member movable to a position to engage and hold the pawl device out of cooperative position with respect to the ratchet wheel, said member normally being held by the retaining pawl in inoperative position, and means adapted to move the retaining pawl to inoperative position and to thereby effect the movement of said member to its operative position, whereupon the ratchet wheel will be released and returned to its original position, said member while in its said operative position being adapted to maintain the retaining pawl in its inoperative position.

63. In a numbering machine, a series of type wheels, type wheel advancing means including a pawl device, controlling means for the pawl device comprising a ratchet wheel, indexing mechanism having a resilient connection with said ratchet wheel, means for holding the indexing mechanism in any setting thereof, the pawl device being adapted upon each of successive actuations thereof to advance the ratchet wheel against the action of said resilient connection, a retaining pawl coating with the ratchet wheel to prevent backward movement thereof under the action of said resilient connection, a member movable to a position to engage and hold the pawl device out of cooperative position with respect to the ratchet wheel, said member normally being held by the retaining pawl in inoperative position, means adapted to move the retaining pawl to inoperative position and to thereby effect the movement of said member to its operative position, whereupon the ratchet wheel will be released and returned to its original position, and means operable upon the next actuation of the pawl device to effect the return of said member to its inoperative position and the return of the retaining pawl to its operative position.

64. In a numbering machine, a series of type wheels, type wheel advancing means including a pawl device, controlling means for the pawl device comprising a ratchet wheel, indexing mechanism having a resilient con-

nection with said ratchet wheel, means for holding the indexing mechanism in any setting thereof, the pawl device being adapted upon each of successive actuations thereof to advance the ratchet wheel against the action of said resilient connection, a retaining pawl coating with the ratchet wheel to prevent backward movement thereof under the action of said resilient connection, a member movable to a position to engage and hold the pawl device out of cooperative position with respect to the ratchet wheel, said member normally being held by the retaining pawl in inoperative position, means adapted to move the retaining pawl to inoperative position and to thereby effect the movement of said member to its operative position, whereupon the ratchet wheel will be released and returned to its original position, and means comprising a tripper device movable with the pawl device and adapted upon the next actuation of the latter to move said member to its inoperative position and thereby effect the return of the retaining pawl to its operative position.

65. In a numbering machine, a series of type wheels, type wheel advancing means including an oscillatory pawl device, controlling means for the pawl device comprising a ratchet wheel, indexing mechanism having a resilient connection with said ratchet wheel, means for holding the indexing mechanism in any setting thereof, the pawl device being adapted upon each of successive actuations thereof to advance the ratchet wheel against the action of said resilient connection, a retaining pawl coating with the ratchet wheel to prevent backward movement thereof under the action of said resilient connection, a member movable to a position to engage and hold the pawl device out of cooperative position with respect to the ratchet wheel, said member normally being held by the retaining pawl in inoperative position, means adapted to move the retaining pawl to inoperative position and to thereby effect the movement of said member to its operative position, whereupon the ratchet wheel will be released and returned to its original position, and means comprising a tripper device oscillatable with the pawl device and adapted upon the next working stroke of the latter to move said member to its inoperative position and thereby effect the return of the retaining pawl to its operative position.

This specification signed this 9th day of March, 1927.

WILLIAM F. HAUPT.
